UNITED STATES PATENT OFFICE.

JOHN G. CALLAN, OF LYNN, MASSACHUSETTS, ASSIGNOR TO GENERAL ELECTRIC COMPANY,
A CORPORATION OF NEW YORK.

ELASTIC-FLUID TURBINE.

No. 883,932.

Specification of Letters Patent.

Patented April 7, 1908.

Application filed October 5, 1906. Serial No. 337,545.

To all whom it may concern:

Be it known that I, JOHN G. CALLAN, a citizen of the United States, residing at Lynn, county of Essex, State of Massachusetts, have invented certain new and useful Improvements in Securing the Buckets of Elastic-Fluid Turbines, of which the following is a specification.

This invention relates to means for securing the buckets of elastic-fluid turbines to the bucket-wheels or other carriers.

In view of the centrifugal strains developed at high speeds it is necessary to provide strong and unyielding fastening devices when separately - formed buckets, or segmental bases carrying a plurality of buckets, are attached to the periphery of a bucket-wheel. In addition to resisting centrifugal strains, provision must be made for holding the buckets rigidly in a given plane of revolution, since any deflection therefrom might wreck the machine by causing the buckets to strike the stationary intermediates.

My invention aims to accomplish the desired results in a simple and comparatively inexpensive manner. To this end the shank of the bucket, or the segmental base support for a plurality of buckets is provided on one side with a shoulder which engages underneath an overhanging flange along one edge of a groove in the wheel or other carrier. The parts are prevented from separating by a filling placed in the groove after the bucket or segmental base has been dropped in and slid laterally to engage the shoulder under the flange. The filling is a strip or ribbon of metal wound into the groove; its width being just sufficient to fill the space between the wall of the groove and the side of the bucket-shank, or segmental/base. The end of the ribbon is fastened in any suitable manner and the outer convolution is secured at one or more points by staking over its edges the adjacent metal of the bucket-shank or segmental base, and of the wheel or other carrier in which the groove is made. The coil of ribbon exerts great resistance to centrifugal force, so that the staking is only necessary to retain the outer layer. The ribbon forms a solid filling, so that the bucket or segmental base is rigidly supported and cannot be deflected from its proper position.

In the accompanying drawings, Figure 1 shows a section of a bucket-wheel having two bucket - carriers riveted to its sides, and

buckets or segmental bases fastened thereto in accordance with my invention; Fig. 2 is a sectional elevation taken on the line 2—2, Fig. 1; Fig. 3 shows one mode of securing the outer end of the ribbon; and Fig. 4 is a section showing a modification.

By the word "carrier" I designate either a wheel having a rim heavy enough to be grooved to receive the buckets, as shown in Fig. 4, or a separate grooved ring 1 attached to the web 2 of the wheel proper, as in Fig. 1. In this figure, two carriers are shown, one on each side of the web, to which they are fastened by through rivets 3. Each carrier has a lip 4 engaging a groove in the web 2 to relieve the rivets from shearing strains. In each carrier is a peripheral groove, having vertical walls, one of which is undercut to form an overhanging flange 6. The bucket 7 may be separately formed, and provided with a shank, or several buckets may be secured to or formed integral with a segmental base; the shank on the base being shown at 8, and constituting a bucket-support. It is narrower than the groove in the carrier, so that it can be readily dropped therein. On the side adjacent to the flange 6 the bucket-support 8 has a shoulder 9 adapted to engage easily but neatly under said flange. These interlocking elements resist all the centrifugal strains to which the buckets are subjected. On the opposite side of the bucket-support 8, between it and the opposite wall of the groove, is wound a metal retainer, such as the ribbon 10, of a width just sufficient to fill the space snugly, so that the edges of the ribbon abut respectively against the bucket-support 8 and the wall of the groove, and the part 8 is rigidly supported in the groove and prevented from any lateral play. The outer end of the ribbon is firmly fastened, as, for instance, by being folded back and abutting against lips 11 staked over from the adjoining portions of the carrier and the bucket-support. The coil of ribbon is capable of withstanding enormous centrifugal strains. It should be composed of a material that does not easily stretch, so that it can be wound under considerable tension if preferred. It may be made a trifle wider than the space it is to fill, so as to require tamping or ramming to make it enter said space. The outer layer may be fastened at intervals by staking the metal of the carrier and the bucket-support, as indicated at 11. This ribbon fastening is

easily and quickly applied, and is reasonable in cost. It is illustrated in Figs. 1 and 2, as applied to a wheel having two carriers attached to it; but the invention is equally well adapted for wheels having a greater or less number of grooved carriers, or to those in which the groove is formed directly in the wheel itself. Such a construction is shown in Fig. 4, which illustrates also a further modification in that the groove is not undercut, and the shoulder on the bucket-support is located on the opposite side and is wide enough to abut against the opposite wall of the groove and have the ribbon wound in above it.

In accordance with the provisions of the patent statutes, I have described the principle of operation of my invention, together with the apparatus which I now consider to represent the best embodiment thereof: but I desire to have it understood that the apparatus shown is only illustrative, and that the invention can be carried out by other means.

What I claim as new, and desire to secure by Letters Patent of the United States, is,—

1. In a turbine, the combination with a grooved bucket-carrier, of buckets mounted in but not filling the groove, and a retainer wound into said groove after the buckets are mounted in place.

2. In a turbine, the combination with a grooved carrier, of a bucket-support received

in but not filling the groove, and a retainer wound into said groove in the space not occupied by said support after the latter is mounted in place.

3. In a turbine, the combination with a grooved carrier, of a bucket support mounted in but not filling the groove, and a flat ribbon wound in the unoccupied space in said groove and of sufficient width to fill said space.

4. In a turbine, the combination with a carrier having a groove, of a bucket-support having a shoulder and received in said groove, and a ribbon wound into and filling the space between the bucket-support and one wall of said groove.

5. In a turbine, the combination with a carrier having a groove provided with an undercut part, of a bucket-support having a portion engaging with the undercut part of said groove, and a retainer wound into said groove.

6. In a turbine, the combination with a grooved carrier, of bucket-supports mounted therein, a ribbon wound into the groove to retain said supports, and lips staked over the ribbon to secure it in place.

In witness whereof, I have hereunto set my hand this third day of October, 1906.

JOHN G. CALLAN.
